ROTATABLE ELECTRICAL CONNECTION

Dwight M. Phillips, Fullerton, Calif., assignor to
 Chiksan Tool Company, Brea, Calif., a corporation of California

Application July 5, 1943, Serial No. 493,544

6 Claims. (Cl. 173—324)

1

This invention relates to devices for connecting electrical conductors and relates more particularly to a swivel joint or swing joint for connecting multiple conductors. A general object of this invention is to provide a practical, effective and long wearing rotary connection for telescopically related electrical conductors.

Another object of this invention is to provide a connection of the character referred to embodying positive and dependable anti-friction means connecting the sections or assemblies for relative rotation.

Another object of this invention is to provide a connection of the character referred to in which the relatively rotatable conductor receiving parts are electrically connected independently of the anti-friction mechanical connection so that the transmission of electrical energy such as high frequency current is unaffected by operation of the anti-friction connecting means.

Another object of this invention is to provide a connection of the character mentioned that is effectively sealed against the entrance and escape of fluid.

Another object of this invention is to provide an electrical connection of the character referred to that is compact and light in weight, and that may be readily inspected and serviced.

The various objects and features of my invention will be fully understood from the following detailed description of a typical preferred form and application of the invention, throughout which description reference is made to the accompanying drawings, in which:

Fig. 1 is a longitudinal detailed sectional view of the connection with a portion appearing in side elevation. Fig. 2 is an elevation view of one end of the connection. Fig. 3 is an enlarged fragmentary longitudinal detailed sectional view showing the means for connecting the several elements of one of the assemblies and Fig. 4 is an elevation view of the other end of the connection.

The improved electrical connection of the present invention may be said to comprise, generally, two body sections A and B, means 10 connecting the sections A and B for relative rotation, means 11 for transmitting electrical energy through the sections A and B independently of the means 10, inner contact means 12 for inner electrical conductors and other elements the functions and details of which will be more fully described.

The body sections A and B constitute an outer tubular assembly which supports and contains the various other parts. The section A is preferably sectional to facilitate the assembling and

2

servicing of the connection. In the construction illustrated the section A comprises two elongate parts 13 and 14. The part 13 has a radial flange 15 at its inner end and has a tubular lip 16 extending axially beyond the flange 15. The part 14 preferably has an external diameter substantially the same as that of the flange 15 and is engaged over the lip 16 to have its inner end oppose the face of the flange. A gasket 17 is provided between the end of the part 14 and the face of the flange 15. Screws 18 are passed through openings in the flange 15 and are threaded into openings in the part 14 to connect the parts 13 and 14. The part 14 is stepped or graduated in internal diameter so that it is of greater wall thickness at its inner portion. The outer end of the part 14 may have an external flange 19 for coupling with other equipment.

The section B may be a simple, tubular part 20 and is received in the part 14 of the section A with clearance. In the construction illustrated the section B is of uniform internal and external diameter and is entirely received within the part 14.

The means 10 for connecting the sections A and B for free relative rotation is operable to assume and transmit axial thrusts in both directions and radial thrusts in all directions, and thus positively connects the sections. The means 10 includes or provides one or more pairs of registering annular grooves 20 in the interior of the part 14 and the exterior of the section B. In the case illustrated there are two spaced pairs of grooves 20. The grooves 20 have concave walls 35 and are formed to define races of round or cylindrical transverse cross section. Series of balls 21 are provided in the registering grooves 20 to connect the sections A and B for free relative rotation. The engagement of the balls 21 in the race grooves 20 holds the section B in spaced relation to the internal surface of the part 14. It will be seen that the spaced series of balls 21 engaged in the grooves 20 are effective in maintaining the sections A and B in the true concentric relation and positively prevent disconnection and displacement of the sections while allowing for free relative rotation between them. Radial openings 22 are provided in the wall of the part 13 to communicate with the pairs of grooves 20 to permit the insertion of the balls 21 into the grooves. The openings 22 are closed by threaded plugs 23. The plugs 23 are provided at their outer ends with intersecting kerfs or grooves 24 and lock wires 25 are engaged around the part 14 and co-operate with the grooves 24 to lock the lugs in

the correct positions. The lock wires 25 may be set in annular grooves in the periphery of the part 14.

Means is provided for sealing between the sections A and B to prevent the entrance of water and other fluids into the connection. External annular grooves 26 are provided in the section B. The grooves 26 are spaced beyond the pairs of registering race grooves 20. In the case illustrated the grooves 26 are square in transverse cross section. Sealing rings 27 of synthetic rubber or the like are provided in the grooves 26. Diagonal grooves 28 are provided in the outer corners of the sealing rings 27. The grooves 28 face outwardly and toward the outer end of the section B. The sealing rings 27 tightly fit the grooves 26 and the diagonal grooves 28 give the sealing rings additional resiliency at their active corners to better seal with the surfaces of the section B and part 14. It will be seen how the sealing rings 27 spaced at opposite sides of the anti-friction connecting means 10 prevent the entrance of fluids and foreign matter into the connection.

The means 11 serves to conduct electrical energy through the sections A and B and the outer assembly. The section B is prepared for connection with an outer conductor or conductor assembly. As illustrated, an outer tubular conductor 30 enters a tapered socket 31 in the outer end of the part 14. A flange 32 is secured to the end of the part 14 by spaced screws 33 and has a complementary socket 34. The conductor 30 has an outer protective sheath and cover over the sheathing. A sheathing wedge 35 is located within the sockets 31 and 34 and serves to secure the sheathing of the conductor 30 within the sockets. It will be seen that upon tightening of the screws 33 the conductor 30 is securely fixed to the section A. A flange part of the wedge 35 may be clamped between the flange 32 and the end of the part 14 and a gasket 36 may be engaged between the flange and the end of the part.

A swing nipple 37 of conducting material such as brass, or the like, enters the section B from its outer end and extends completely through the section B to enter the part 14 of the section A. A square flange 38 may be provided on the outer end of the nipple 37 to facilitate its attachment to other equipment. The nipple 37 passes through the section B with considerable clearance and the invention provides means for insulating the nipple from the section B. This means includes an insulating sleeve 39 which enters the outer end of the section B and closely engages about the nipple 37. A flange 40 is provided on the outer end of the sleeve 39 and has spaced notches in its periphery. Lugs 41 project from the end of the section B and cooperate with these notches to rotatably connect the section B and sleeve. A lock nut 42 is threaded on the nipple 37 and clamps against the end of the sleeve 39. A similar insulating sleeve 43 enters the section B from its inner end and closely engages about the nipple 37. A flange 44 is provided on the sleeve 43 adjacent its end and is provided with spaced peripheral notches 45 (see Fig. 3). Lugs 46 extend from the end of the section B and cooperate with these notches to secure the section B and the sleeve 43 against relative rotation. The end of the insulating sleeve 43 has spaced notches 47 and lugs 48 project from the surface of the nipple 37 and cooperate with the notches 47 to connect the insulating sleeve 43 and the nipple 37 against relative rotation. With the construction just described the nipple 37 of conducting material is completely

insulated from the section B and is connected with the section B to rotate or remain stationary therewith.

Brush means are provided to electrically connect the swing nipple 37 and the section A to provide for the transmission of electrical energy through the tubular outer assembly. Two diametrically opposite radial openings 49 are provided in the thick-walled portion of the section A. Carbon brushes 50 are slidable in the inner portions of the openings 49 and their inner ends are engageable with the periphery of the nipple 37. Plugs 51 are threaded in the outer portions of the openings 49 and springs 52 are engaged under compression between the brushes 50 and inner ends of the plugs 51. The springs 52 constantly urge the brushes 50 inwardly against the nipple 37 to maintain electrical connection between the nipple and the section A. In the drawings the openings 49 are shown in alignment with the screws 18 but in practice it will probably be preferred to offset the openings 49 from the screws 18.

The inner contact means 12 is provided to electrically connect inner electrical conductors. An assembly of insulators is provided within the tubular outer assembly to support the inner contact means 12. A tubular insulator 53 of porcelain or the like is secured in the part 13 by porcelain cement 54 and extends axially inward in spaced relation to the internal walls of the part 13 and nipple 37. An elongate insulator 55 of porcelain, or the like, is secured in the inner portion of the sleeve or nipple 37 by cement 56. A deep socket 57 is provided in the inner end of the insulator 55 and receives the insulator 53 with clearance. A similar socket 58 is provided in the outer end of the insulator 55.

The inner contact means 12 includes a contact plug 59 of conducting material secured in the inner portion of the tubular conductor 53 by solder 60, or the like. Wax 61 may line the interior of the insulator 53 and the adjacent interior of the part 13 to provide a flush internal surface and may cover the end of the contact plug 59. A conductor 62 provided with a sheath 63 of rubber, or the like, extends longitudinally through the outer conductor 30 with clearance and enters the connection assembly. The conductor 62 has its end portion secured in the contact plug 59. The active exposed end of the contact plug 59 is broadened by a flange 64 and presents a flat surface of substantial extent. The conductor 62 may pass through the contact plug 59 to have its end exposed at the active face of the plug.

The insulator 55 has a central longitudinal opening 65 connecting its sockets 57 and 58. The stem 66 of the contact member 67 extends through the opening 65 and is secured therein by porcelain cement 68, or the like. The stem 66 extends into the socket 58 and its projecting portion has a socket 69 for the reception of an inner conductor. The socketed end portion of the stem 66 may have spaced saw-cuts or slots 70 so that it is resilient to better grip the conductor. The contact member 67 is disposed within the inner portion of the socket 57 of the insulator 55 and may be fixed therein by the cement 68. A socket 71 is formed in the end of the contact member 67. The socket 71 is eccentric or offset with respect to the longitudinal axis of the connection.

A polygonal or square tube 72 of copper, or the like, is secured in the socket 71 by solder, or the like. The tube 72 projects axially from the member 67 toward the contact plug 59. A carbon

brush 73 is slidable in the outer portion of the tube 72 and projects from the tube. The projecting end of the brush 73 is engageable with the broad face of the contact plug 59 and the exposed end of the conductor 62. A spring 74 is provided within the tube 72 and is arranged under compression between the bottom of the socket 71 and the inner end of the brush 73. The spring 74 constantly urges the brush 73 against the end of the contact plug 59 and the conductor 62 to maintain electrical connection between the plug 59 and the contact member 67. It is to be observed that the contact plug 59 is rigid with relation to the section A and that the contact member 67 is rigid with relation to the section B and the brush 73 maintains electrical connection between the relatively rotatable contact elements.

It is believed that the operation of the electrical connection will be readily understood from the foregoing detailed description. The balls 21 engaged in the spaced race grooves 20 dependably connect the sections A and B for free relative rotation and maintain the sections in the concentric relation. The means 11 provides for the uninterrupted transmission of electrical energy through the outer tubular assembly and by-passes or is independent of the anti-friction connection 10. The inner contact means 12 is dependably insulated from the outer tubular assembly and is effectively supported between two large insulators 53 and 55. The brush 73 cooperating with the plug contact 59 provides for the uninterrupted transmission of electrical energy between the two internal conductors.

Having described only a typical preferred form and application of my invention, I do not wish to be limited or restricted by the specific details herein set forth, but wish to reserve to myself any variations or modifications that may appear to those skilled in the art or fall within the scope of the following claims.

Having described my invention, I claim:

1. An electrical connection including two tubular sections telescoping one within the other, one section being a bearing sleeve and the other a jacket around the sleeve, anti-friction members between the interior of the jacket and the exterior of the sleeve keying the sections together against relative axial movement and connecting the sections for free relative rotation, means for securing a conductor to the jacket section, an elongate tubular conducting nipple extending centrally through the bearing sleeve and adapted to be secured to another conductor, means around the nipple rigidly securing the nipple in the bearing sleeve and including electrical insulation insulating the nipple from said sleeve, and contact means within one of the sections remote from the anti-friction members maintaining electrical connection between the nipple and the jacket section.

2. An electrical connection including two tubular sections with telescoping parts, one a bearing sleeve and the other a jacket around the sleeve, anti-friction means including members between the sleeve and jacket bearing in the jacket and on the sleeve keying the sections together against relative axial movement and connecting the telescoping parts of the sections for free relative rotation, means on one section for securing a conductor thereto, an elongate tubular conducting nipple extending through the bearing sleeve and adapted to be connected with another conductor, insulators within the bearing sleeve and surrounding the nipple and fixing the nipple in the

other section and insulating the nipple therefrom, and means within one of the sections remote from the sleeve and said members for maintaining the nipple in electrical connection with the first named section.

3. An electrical connection including two tubular sections with telescoping parts one a bearing sleeve and the other a jacket around the sleeve, anti-friction members between and connecting said parts of the sections for free relative rotation, said members bearing in the jacket and on the sleeve and keying the sections together against relative axial movement, means on one section for securing a conductor thereto, an elongate tubular conducting nipple extending through the sleeve and adapted to be connected with another conductor, insulators fixing the nipple in the bearing sleeve and insulating the nipple therefrom, and means axially removed from the anti-friction members and bearing sleeve maintaining the nipple in electrical connection with the first named section, the last named means including one or more brushes on said first named section cooperating with the nipple.

25 4. An electrical connection including two tubular sections one having a jacket portion and the other having a bearing sleeve in the jacket portion, anti-friction members between the sleeve and jacket connecting the sections for free relative rotation and keying the sections against relative axial movement, means on one of the sections for securing a conductor thereto, a tubular conducting nipple extending through the anti-friction members independently thereof and concentric with the sleeve and adapted to be connected with another conductor, insulator means extending lengthwise of the nipple securing the nipple in the other of the sections through the sleeve and insulating the nipple therefrom, means 30 beyond one end of the insulator means maintaining the nipple in electrical connection with the first named section, and a first inner contact within and insulated from the nipple and said first named section for connection with an incoming conductor, and a second inner contact within the nipple and in contact with the first inner contact for connection with an incoming conductor.

5. An electrical connection including two tubular sections one having a jacket portion and the other having a bearing sleeve in the jacket portion, anti-friction means including members between the sleeve and jacket connecting the sections for free relative rotation and keying the sections against relative axial movement, means on one section for securing a conductor thereto, a central tubular conducting nipple adapted to be connected with another conductor, insulator means extending lengthwise of the nipple securing the nipple in the sleeve and insulating the nipple therefrom and located between the nipple and the antifriction members, means beyond one end of the insulator means maintaining the nipple in electrical connection with the first named section, inner insulators within and fixed to the nipple and said first named section, and inner contact means carried by said inner insulators including contacts supported by said inner insulators in contact with each other and for connection with incoming conductors.

6. An electrical connection including two tubular sections one having a jacket portion and the other a bearing sleeve within the jacket portion, anti-friction means including bearing members 75 between the sleeve and jacket bearing in the

7
 jacket and on the sleeve and connecting the sections for free relative rotation and keying the sections together against relative axial movement, means on one section for securing a conductor thereto, a central tubular conducting nipple in the inner section and within the sleeve and adapted to be connected with another conductor, insulator means extending lengthwise of the nipple securing the nipple in the sleeve and insulating the nipple therefrom, means beyond one end of the insulator means maintaining the nipple in electrical connection with the first named section, an insulator fixed in said first named section, a contact on the insulator presenting a flat axial face, an insulator fixed in the nipple, a contact member on the last named insulator, means on the contact and contact mem-

ber for receiving inner conductors, and a spring urged brush contact on the member for engaging said face.

DWIGHT M. PHILLIPS.
